UNITED STATES PATENT OFFICE.

EDWARD HOERNEL, OF RACINE, WISCONSIN, ASSIGNOR OF ONE-HALF TO HUBERT E. PECK, OF WASHINGTON, DISTRICT OF COLUMBIA.

KEY-DUPLICATING MACHINE.

1,165,099.

Specification of Letters Patent. Patented Dec. 21, 1915.

Application filed September 6, 1913. Serial No. 738,460.

To all whom it may concern:

Be it known that I, EDWARD HOERNEL, a citizen of the United States, residing at Racine, in the county of Racine and State of Wisconsin, have invented certain new and useful Improvements in and Relating to Key-Duplicating Machines, of which the following is a specification.

This invention relates to certain improvements in and relating to key duplicating machines and the like; and the objects and nature of the invention will be readily understood by those skilled in the art in the light of the following explanation of the accompanying drawings illustrating what I now believe to be the preferred embodiments and mechanical expressions from among other formations, arrangements and constructions within the spirit and scope of the invention.

An object of the invention is to provide what might be termed an automatic machine for cutting key blanks to form keys for pin tubular locks, and for other purposes, wherein various improved adjustments and features are embodied with the ends in view of attaining accuracy, speed and durability.

A further object of the invention is to provide certain improvements in the construction, arrangement and combinations of parts whereby a highly efficient and improved machine will be produced for duplicating keys and other articles.

A further object of the invention is to provide a machine for cutting key blanks to duplicate pattern keys, or the like, and wherein a feed carriage is automatically driven from and parallel with the axis of rotation of the cutting tool and carries a pattern and blank carriage automatically movable toward and from said tool or radially with respect thereto.

The invention consists in certain novel features in construction and in combinations and arrangements as more fully and particularly set forth and specified hereinafter.

Referring to the accompanying drawings:—Figure 1, is a perspective of the machine, as in operation duplicating a key. Fig. 2, is a top plan of the machine as it appears in Fig. 1. Fig. 3, is a bottom plan of the machine. Fig. 4, is a side elevation. Fig. 5, is a cross section on the line 5—5; Fig. 2. Fig. 6, is a cross section on the line 6—6, Fig. 2. Fig. 7, is a longitudinal section on the line 7—7, Fig. 2. Fig. 8, is a detail per-

spective of certain parts showing the same separated. Fig. 9, is a detail elevation of a portion of the machine showing a modified construction. Figs. 10, 11, 12, 13 and 14, are detail views of various parts of the machine.

In the specific example illustrated in the accompanying drawings, the operating parts are carried by a hollow base 1, on one end of which the hollow head stock 2, is rigidly secured. The arbor 3, carrying the rotary milling or other suitable cutting tool 4, is carried by and mounted in said head stock, and is provided with any suitable driving means for driving the arbor by hand or by power as may be desired. For instance, I show the arbor provided with driving pulley 5, which if so desired can be provided with handle 6. I show the arbor provided with a pair of opposed or oppositely tapered bearing cones 7, 8, engaging correspondingly tapered bearing surfaces of the head stock. The cone 7, is adjustable longitudinally of the arbor to take up wear, and the arbor is provided with locking or jam nut 9, for locking said cone 7, in the desired adjustment. The cones are arranged at opposite end portions of the arbor, and the conical bearing surfaces therefor in the head stock are arranged at the opposite edge portions of said head stock, while the portion of the arbor between the cones and within the head stock is threaded to form a screw or worm 10, for driving the feed carriage as herein-after more fully described. The adjustable cone and its locking nut are accessible in the space between the driving wheel or pulley and the adjacent edge of the head stock. An exceedingly accurate and durable mounting for the arbor is thus provided, but I do not wish to limit my invention thereto, although I consider it one of the specifically desirable features thereof.

The top of the base is formed with a suitable guide or slideway 11, elevated above the general horizontal plane of the base top and arranged transversely across the same. This slideway is parallel with the longitudinal axis of the cutting tool arbor, and is located a suitable distance in advance of the head stock carrying said arbor.

A suitable feed carriage 12, is arranged on and confined to the slideway to reciprocate transversely of the base and longitudinally of the slideway, and consequently the

path of movement of the feed carriage is parallel with the longitudinal axis of the cutting tool arbor. The slideway holds the feed carriage against lateral movement toward and from the cutting tool and its arbor, as well as against vertical movement.

The feed carriage is provided at its top or upper side with a guide or slideway 13, extending completely across the carriage 10 from front to rear and hence arranged at right angles or transversely with respect to the slide way to which the carriage is confined. A work-and-pattern-carrying head or carriage 14, is carried by and mounted on the feed carriage and is movable thereon toward and from the cutting tool. The head 14, is longitudinally elongated and in this instance I show the same comprising a flat horizontal elongated body or main plate 15 confined in and at its ends projecting beyond the ends of the slideway. The longitudinal edge portions of said body of the head 14, are beveled to fit under the overhanging edge walls of the slideway 13 of the feed carriage, whereby the head is held against vertical and lateral movements with respect to the feed carriage and is confined to longitudinal sliding movement toward and from the cutting tool.

30 At the upper side of the rear end of the head 14, that is, at the end thereof adjacent to the cutting tool, I provide a clamp or holder for the key blank or other article to be cut, while at the upper side of the front 35 end portion of the head, I provide a clamp or holder for the pattern key or other article to be duplicated by the action of the cutting tool on the blank. These two holders are arranged in tandem longitudinally of the 40 head and are spaced a distance apart to receive a gage or stop fixed to the base and projecting laterally into the space between said holders to engage the notched edge of the pattern key clamped by the front holder 45 and projecting rearwardly therefrom, and to thereby control the movement of the head toward the cutting tool.

Suitable mechanism is provided constantly acting on the head to yieldingly hold 50 the same toward the cutting tool and the pattern key edge against said stop or gage. In the particular instance illustrated, this mechanism consists of a horizontal rock shaft 15, arranged transversely of the base 55 and with respect to the head and mounted in journal boxes 16, fixed to and rising from the front end of the base in advance of the front end of the head. This rock shaft is provided with a radial arm or toe 17, rigid therewith and rising therefrom and constantly pressed forward into engagement with the straight front edge of a horizontal flange 18, fixed to the front end of the head and arranged transversely thereof and projecting forwardly therefrom. The length

of this flange is at least equal to the length of the feeding stroke of the feed carriage. The rock shaft is provided with means constantly tending to rock the same in a direction to hold the arm 17, rearwardly against the flange of the head with sufficient force to hold the head at its limit of forward movement as determined by the notched edge of the pattern key in engagement with the stop or gage. Various means can be provided 75 for this purpose, although I now prefer to employ the action of gravity through the medium of a lever 19, fixed to the shaft 15, and depending therefrom through an opening in the top of the base and having an 80 elongated horizontally disposed rearwardly extending portion which can be provided with a weight 20, if so desired.

The feed carriage, carrying the head, is actuated on its feed stroke transversely of the base and from left to right (in the particular arrangement of Fig. 1) by the rotation of the cutting tool arbor through the medium of a rack and pinion and suitable gearing operatively connecting the same to 90 the worm 10, of the arbor. In the particular example illustrated, the head stock is fixed on and rises from the rear end of the top of the base and is formed hollow and the base top is formed with an opening registering with the cavity within the head stock. Within the head stock, I provide a vertically rotating worm gear 21, meshing with and rotated by the worm 10, of the arbor, and this worm gear is provided with a pinion 103 22, fixed thereto and driven thereby. The worm gear and its pinion are carried by and rotate on a horizontal stud 23, arranged longitudinally with respect to the base. This stud is adjustably secured at its front end to the front wall of the head stock by a nut 24, on the projecting threaded front end of the stud. The front wall of the head stock is formed with a slot through which the stud end projects, and whereby the stud can be 110 adjusted vertically to maintain the desired operative relation between the worm gear and the worm of the arbor.

The worm gear pinion 22, is in constant mesh with a gear 25, loosely mounted on a horizontal feed shaft 26, arranged longitudinally of and within the base and at its front end provided with a pinion 27, rigid therewith. This pinion 27, is in constant mesh with a rack 28, fixed to the feed carriage and transversely arranged with respect to the base but longitudinally arranged with respect to said carriage. The rack bar is secured to the feed carriage through the medium of an angle plate or bracket 29, arranged centrally of the carriage and bolted to the under side thereof and depending therefrom through a slot in the base top arranged longitudinally and centrally of the slideway 11. The rack bar 28, is arranged 130

longitudinally of the depending portion of the bracket 29, and is clamped thereto in vertical adjustment by bolts 30, extending through vertically elongated openings in the 5 bracket.

The longitudinal feed shaft 26, is mounted in and carried by a bracket 31, arranged within the base and normally fixed to a depending wall of the base by bolts 32. This 10 bracket is vertically and laterally adjustable to maintain the desired operative position of its gear and pinion with respect to coöoperating parts, by providing enlarged holes in the bracket for the reception of the 15 transverse clamping bolts 32, that extend through the bracket and screw into the base wall and clamp the bracket rigidly thereagainst. By loosening these bolts the bracket can be shifted to a slight extent vertically or longitudinally of the base to attain the desired adjustment of the shaft 26.

The gear 25, is loosely mounted on the longitudinal shaft 26, so that said shaft can rotate freely therein and independently 25 thereof, and a suitable clutch device is provided for locking said gear to said shaft for driving the feed carriage on its feed stroke. For instance, I show the gear 25, located between a collar 34, fixed on the shaft and arranged 30 between the front side of the gear and the shaft carrying bracket, and a nut 35, longitudinally adjustable on the screw threaded rear end of the shaft and projecting rearwardly through an opening in the 35 depending rear wall of the base and provided with a milled head 36, exposed and accessible at the exterior of the rear end of the base. By rotating this nut in one direction, the gear 25, will be clamped between 40 the front end of the nut and said collar 34, and will be thereby locked to the shaft and will drive the shaft. By rotating the nut in the opposite direction, the gear will be released from the shaft so that the feed carriage 45 can be moved by hand on its return stroke and toward the left (arrangement of Fig. 1) to the point or limit from which the carriage starts on its feed stroke. When the carriage has completed a feed stroke, the 50 nut 35, is loosened and the carriage is moved back by hand on its return stroke, and the shaft 26, freely spins in the gear 25. When the carriage has thus been returned to the starting point, the nut is tightened to lock 55 the gear to the shaft to drive the carriage on its feed stroke when the cutting tool arbor is actuated.

The work or blank holder A and the key or pattern holder B, are similar in construction and adjustment and in fact are interchangeable, although separately manipulated in opening, closing and adjustment.

These holders are arranged to hold the key a, and blank b, in horizontal positions and 65 in parallelism and arranged transversely of

the head and longitudinally with respect to the direction of movement of the feed carriage and parallel with the axis of rotation of the cutting tool. The blank holder maintains the blank projecting rearwardly therefrom with its longitudinal edge against the cutting edge of the cutting tool, while the key holder maintains the key with its notched edge exposed rearwardly beyond said key holder and in engagement with the edge of the gage or stop, and as said two holders are arranged in tandem, the key and blank are alined and held in a common horizontal plane, although I do not so wish to limit all features of my invention.

The body plate of the head carrying the holders A, B, is formed rigid with elevated seats or bases 37, for said holders, respectively. These seats are similar, and each is formed with a central vertical screw threaded socket, a flat horizontal top face, and a surrounding depressed shoulder 38. The clamp of each holder consists of a lower rectangular plate or jaw 39, having a central vertical bolt hole, an upper rectangular plate or jaw 40, having a central vertical bolt hole, and a clamping bolt or screw 41, passing down through said holes and into said socket and at its upper end having a suitable head whereby the screw can be rotated to tighten or loosen the clamp or to remove the screw therefrom if need be.

The lower jaw or plate 39, removably rests horizontally on its seat 37, and at its under side is formed with depending edges 42, to engage the depressed shoulders 38, and thereby center the jaw on the seat with the bolt hole of the jaw alined with the threaded socket of the seat. The shoulders 38, and edges 42, are so arranged that by slightly lifting the jaw (when the clamping screw is unscrewed to the necessary extent) to carry the edges above the seat, the jaw can be turned horizontally about the screw to present either end thereof at the clamping position, and the jaw can then be dropped onto its seat and the edges will properly fit the shoulders to hold the jaw centered. The upper face of the jaw is formed with a pair of V-grooves 44, arranged in front of and behind the bolt hole. These grooves are straight and parallel and extend completely across the jaw. One end of the upper face of the jaw is formed with a depressed flat seat and shoulder 45, between one groove 44, and the adjacent end edge of the jaw, while the opposite end of the jaw is formed with a rib 46, parallel with the grooves 44, and rounded or semi-cylindrical in cross section and separated from the adjacent groove 44, by an intervening depression.

The upper jaw 40, at its under side has a pair of V-grooves 44', corresponding to the grooves 44, of the lower jaw and adapted to 130

co-incide therewith. At one end, the under side of the upper jaw is formed with a rounded rib 46', similar to the rib 46, and at its opposite end, the under side of the upper jaw is formed with a flat surface 45', adapted to co-incide with the depressed seat that terminates in shoulder 45, of the lower jaw. The upper jaw is formed with the convexed upper surface 48, at its crown or highest portion engaged by the head of the screw 41, when tightened to clamp the key or the blank. The upper jaw can be reversed to bring either end thereof to clamping position.

15 The two jaws of a clamp are not pivoted together although in action the upper jaw rocks on an axis or fulcrum in clamping the key or blank. To accomplish this result and yet permit reversal of either of the 20 jaws of a clamp, I provide each clamp with a removable cylindrical fulcrum pin 49, provided with end heads 50. This fulcrum pin rests in the V-groove at the front end of the lower jaw, while the corresponding V- 25 groove at the front end of the upper jaw receives said pin and the upper jaw is rockable thereon to bring its rear end into and from clamping relation with respect to the rear end of the lower jaw. The end heads 30 50, engage the vertical side edges of both jaws and maintain said jaws accurately in alinement. Each jaw is provided with V-grooves at its opposite ends so that either or both jaws can be reversed to present 35 either end at the rear or clamping position.

The rounded ribs 46, 46', of the jaws are provided to enter the grooves cut longitudinally of and in the sides of most keys for pin tumbler locks. Keys for some pin tumbler locks have these grooves on one side, while keys for other pin tumbler locks have said grooves on the other side, and the grooves in keys for different locks vary in width, depth and cross sectional formation, 45 while keys for some pin tumbler locks are not provided with side grooves, and some keys have longitudinal grooves on both sides but located at different distances from the rear edges of the keys.

50 When a key without side grooves is to be duplicated, the jaws of the two holders A, B, are arranged so that the ends of the two lower jaws having the depressed seats and shoulders 45, are at the rear clamping positions, and the ends of the upper jaws having the flat faces 45', are at the rear clamping positions see Fig. 12. The key and the blank are then placed on the seats of the lower jaws of their respective holders with their rear edges against the shoulders 45, and the screws of the holders are then turned to rock the upper jaws and bring their rear ends tightly down on the upper sides of the key and blank with their flat faces 45', engaging the same, whereby the

key and blank will be both rigidly held and the rear projection of the edge of the blank will be the same as that of the key by reason of the shoulders 45, against which the blank and key are set.

70 When a key having a longitudinal groove in its upper side adjacent to its rear edge is to be duplicated, the jaws of the holders being in the positions above mentioned to receive a grooveless key and blank, the 75 upper jaws of the holders are reversed, turned end for end, to present their rounded ribs 46', at the rear and above the flat seats of the lower jaws see Fig. 13. The key and blank are then placed on the flat seats 80 of the lower jaws and the upper jaws are rocked so that their rounded ribs will enter said longitudinal grooves near the rear edges of the key and blank and the clamping screws are tightened to lock the key and 85 blank in the desired positions.

When the key to be duplicated has the longitudinal groove near its rear edge at the under side of the key when the key is in position in the clamp, both jaws of each 90 holder are reversed to bring the front ends to the rear, the fulcrum pins being first removed and then re-inserted, the flat faces of the upper jaws will then be above the rounded ribs of the lower jaws at the rear 95 ends of the holders, see Fig. 14, and the key and blank can be inserted and clamped.

95 In order to produce an accurate duplication of a pin tumbler lock key, it is necessary to gage from the centers of the longitudinal 100 grooves in the sides of the keys so that the bottoms of the notches cut in the blank will measure the same distances from the centers of the longitudinal grooves as in the pattern key. For this reason, among others, I provide the jaws of the holders with the ribs to enter said side grooves and thereby clamp the key and blank against the opposing jaws, and I form said ribs rounded so that they will automatically find the centers of said 105 longitudinal grooves whatever the formation or dimensions of said grooves, within certain limits.

110 The jaws of the holders can be adjusted to properly fit and clamp pin-tumbler-lock 115 keys and blanks of various types and formations, and furthermore said jaws can be readily removed from the machine and other jaws substituted to receive and properly hold other patterns and blanks for which the present jaws may not be adapted.

120 The controller, gage or stop against which the edge of the pattern key is held and along which said edge slides and which thereby controls and determines the radial position 125 of the head with respect to the cutting tool, consists of a horizontally disposed rigid arm or block 52, arranged parallel with the axis of rotation of the cutting tool and transversely with respect to the head. At its outer 130

end this gage is clamped or otherwise fixed to a rigid post 53, rising from the left hand side of the base beyond the end of the slide-way 11, and said gage extends laterally, toward the right, from said post a distance above the head and between the holders thereof. At its free end or extremity, this gage is formed with a forwardly projecting beveled blade, tooth or edge 54, to engage the edge of the key and across which said edge of the key slides or travels. The right hand side of this tooth 54, is preferably flat, while the opposite side thereof is preferably beveled for obvious reasons.

15 Suitable means are provided whereby the gage arm can be bodily adjustable toward and from the cutting tool, and also whereby said arm can be bodily adjustable transversely of the base, that is parallel with the 20 axis of rotation of the cutting tool. To accomplish these results, I show the gage arm when in operative adjustment, fixedly secured and clamped by a headed bolt or screw 55, passing down through an enlarged bolt 25 hole 56, in the left hand or secured end of the arm, and through a block 57, and into a vertical screw threaded socket in the post 53. The block 57, is loosely interposed and clamped between the post and gage arm, 30 and the underside of the block and upper end of the post are formed with an intermeshing tongue and groove 58, arranged transversely with respect to the length of the arm to permit bodily adjustment of the arm 35 toward or from the axis of rotation of the cutting tool, when the clamping bolt 55, is loosened. During this adjustment the block 57, slides on the post and the arm moves with the block. The upper side of the block 57, 40 and the under side of the secured end of the gage arm are formed with an intermeshing tongue and groove 59, arranged longitudinally with respect to the gage arm so that the gage arm can be adjusted longitudinally 45 to move its tooth 54, to the right or left, when the screw 55, is loosened and the arm is moved to the right or left on the block 57.

The tongue and groove connections between the gage arm and block and between the block and post rigidly hold and brace the gage arm in the desired adjustment and against play or movement under the action of the head.

When a key is to be duplicated, the feed 55 carriage is moved to the starting position, as shown in Fig. 1, and the pattern key is properly clamped in the forward holder with the handle of the key to the right of the holder and with the shoulder of the key 60 engaging the right hand, flat, side face or free end of the gage arm. The blank to be cut is correspondingly arranged and clamped in the rear holder with the shoulder of the blank against the right hand, or flat side 65 of the cutting tool. The nut 35, is then

turned up tight to operatively connect the arbor and the longitudinal feed shaft, and the machine is thereupon ready for operation. The arbor is actuated by hand, or by power, to rotate the cutting tool in the proper direction and the feed carriage is thereby automatically propelled on its feed stroke toward the right.

The feed carriage carries the head toward the right and hence the key and the blank 70 are moved lengthwise or longitudinally across the gage and the cutting tool. The freely movable head is being constantly pressed toward the cutting tool and the notched edge of the key is thereby held constantly pressed against the beveled tooth of the gage while the edge of the blank is constantly held pressed against the cutting tool. The movement of the head toward 75 and from the cutting tool follows the irregularities or notches in the key edge and hence said notches are exactly duplicated in the edge of the blank by the cutting tool. The beveled tooth of the gage acts as a cam on the notched edge of the key as the same is drawn longitudinally across said tooth, and permits the head to move toward the cutter, as will be readily understood by those skilled in the art. The arrangement is such 80 that the blank edge will be cut to duplicate the key edge by a single operation of the feed carriage, that is, a blank will be cut by a continuous operation during one feed stroke of the feed carriage. The machine 85 will duplicate keys having V-shaped notches as well as keys having U-shaped notches, as will be readily understood. When the feed stroke is completed, the clutch nut 35, is loosened and the carriage moved back to the 90 starting point by hand, and the clamps are opened and the duplicated keys removed.

It is obvious that the sliding head can be constantly pressed toward the cutting tool by a spring device instead of the weight mechanism hereinbefore described. For instance, a plate spring can be fixed on the base with its free rearwardly springing end bearing against the front edge of flange 18, instead of the weighted lever see Fig. 9, or 110 a coiled spring might be coupled to the rock shaft to hold the toe 17, against the flange 18, and pressing the head rearwardly, instead of the weighted lever.

By employing the upper jaws of the holders with arched or convexed upper surfaces, the heads of the clamping screws will always bear down centrally thereon even though different keys or blanks vary in thickness, and hence the draft or strain will 115 always be centrally and longitudinally of the screws.

It is evident that various changes, modifications, and variations might be resorted to in the forms, constructions and arrangements 120

described, that features might be omitted and structures added, without departing from the spirit and scope of my invention as defined by the appended claims and hence I do not wish to limit myself to the exact disclosures hereof.

Desiring to protect my invention in the broadest manner legally possible, what I claim is:—

10. 1. A key duplicating machine comprising a rotary cutting tool and its arbor, a feed carriage having a path of movement parallel with said arbor, a freely slidable head carried by said carriage and movable toward and from the cutting portion of said tool, means independent of said carriage for constantly and yieldingly pressing said head toward said tool, a pattern holder carried by said head, a blank holder carried by said head, a fixed gage arranged to coöperate with the pattern in controlling the movement of said head toward and from said tool, and feed mechanism operatively connecting said arbor and said carriage.
15. 2. A key duplicating machine comprising a rotary cutting tool, a feed carriage movable on its feed stroke in a direction parallel with the axis of rotation of said tool, means for simultaneously rotating said cutting tool and actuating said carriage on its feed stroke, a head carried by said carriage and movable thereon independently thereof toward and from said tool and provided with means to hold a blank to be cut in a position parallel with the direction of movement of said feed carriage and in position to be operated on by said tool, and also provided with means to hold a pattern in a position parallel with said blank, and a gage
20. 3. A key duplicating machine comprising a base provided with a head stock, an arbor mounted in said head stock and provided with actuating means and also provided with a rotary cutting tool, said arbor being provided with a pair of oppositely arranged cone bearings and said head stock being provided with opposite conical bearing surfaces receiving said cones, one of said cones being adjustable on said arbor and being accessible at the exterior of said head stock, said arbor being formed with a worm between said cones, a feed carriage movable on said base, mechanism for actuating said carriage on its feed stroke, said mechanism being operatively connected with said worm, said carriage provided with means to hold a blank to be cut in operative position with respect to said cutting tool, and controlling means determining the position of the blank with respect to the tool.
25. 4. A key duplicating machine comprising a base, a head stock rising therefrom, an arbor mounted in said head stock and provided with a cutting tool and actuating means, said base provided with a slide way parallel with said arbor, a feed carriage 70 confined to said slide way and slidable longitudinally thereof, feed mechanism operatively connecting said arbor and said carriage to actuate said carriage on its feed stroke by the rotation of said arbor, a head carried by said carriage and provided with pattern and blank holders, said head having a movement independently of said carriage and being constantly and yieldingly pressed in one direction, and a gage carried by the 75 base and coöperating with the pattern to control the independent movement of the head.
5. A key duplicating machine embodying a feed carriage to carry the pattern and blank longitudinally during the cutting operation, a cutting tool, gearing connecting said tool and said carriage to automatically actuate the carriage on its feed strokes, and a head mounted on said carriage and provided with pattern and blank holders and having an independent movement to carry the blank and pattern transversely during the cutting operation, said head having means constantly and yieldingly pressing the same toward operative position, substantially as described.
6. A key duplicating machine comprising a base, an arbor provided with and driving a rotary cutting tool and formed with a worm, 100 a feed carriage, a head carried by said carriage and movable thereon toward and from said tool and provided with pattern and blank holders, a gage to coöperate with the pattern carried by said head to control the movement thereof toward said tool, a rack arranged longitudinally of and secured to said carriage for actuating the same on its feed stroke, a rotary feed shaft having a pinion meshing with said rack to drive the 105 same, a worm gear in mesh with and actuated by said worm, and operative driving connections from said worm gear to said shaft.
7. A key duplicating machine comprising 110 a base, an arbor provided with and driving a rotary cutting tool, a feed carriage carried by said base and provided with and carrying a head having an independent movement transversely of the direction of feed of said carriage, said head provided with means for holding the pattern and blank during the cutting operation, means for controlling the independent movement of the head during the cutting operation according to the edge of the pattern to be duplicated, and actuating gearing from said arbor to said feed carriage.
8. A key duplicating machine comprising 115 a base, an arbor provided with and driving

a rotary cutting tool, a feed carriage mounted on said base, feed mechanism operatively connecting said arbor and said carriage for actuating the carriage on its feed stroke, mechanism for carrying the pattern and the blank and mounted on said carriage, and a gage.

9. A key duplicating machine comprising a base, an arbor provided with and driving a rotary cutting tool, a feed carriage provided with and carrying mechanism for holding the pattern and the blank, a gage for co-operating with the pattern in determining the operative movement of the blank toward and from said tool, and transmission mechanism operatively connecting said arbor and said carriage for actuating the carriage on its feed stroke comprising a rack bar adjustably secured to said carriage and a rotary shaft provided with and mounted in a bracket adjustably secured to the base.

10. A key duplicating machine comprising a base having a head stock, an arbor mounted therein and provided with and driving a rotary cutting tool, a gear operatively connected to and driven by said arbor and provided with a pinion, a stud carrying said gear and its pinion, said stud being adjustably secured to said head stock, a feed carriage movable on said base and provided with and carrying means for holding a pattern and a blank, devices for controlling said means, and actuating connections from said pinion to said carriage for actuating said carriage on its feed stroke.

11. A key duplicating machine comprising a base, a cutting member, a feed carriage provided with and carrying means for holding a pattern and a blank, devices for controlling said means, driving means, and operative connections from said driving means to said carriage for actuating the carriage on its feed stroke, said operative connections including a rotary shaft having a shoulder, a nut adjustable longitudinally on said shaft and having accessible means whereby the nut can be rotated in either direction, and a gear for rotating said shaft and loosely mounted thereon and adapted to be locked thereto between said nut and said shoulder, for the purposes substantially as described.

12. A key duplicating machine comprising a base having a top slideway with a longitudinal opening, a feed carriage confined to and slideable longitudinally of said slide way and provided with a longitudinal bracket depending through said opening, a rack bar arranged longitudinally of and secured to said bracket, a rotary shaft arranged in the base and geared to said bar to actuate the carriage on its feed stroke, a gear for driving said shaft and loosely mounted thereon so that said carriage can be returned by hand without rotating said gear, hand operated means extending to the exterior of said base for

locking said gear to said shaft for driving the same, and an arbor provided with and driving a rotary cutting tool and geared to said gear for actuating the same.

13. A key duplicating machine comprising a base, cutting means, a movable head provided with holders for the pattern and blank, actuating mechanism, and controlling means comprising a gage arm fixed to the base and adjustable longitudinally and laterally, a slide block interposed between the arm and base and having a tongue and groove connection with the arm and also having a tongue and groove connection with the base and a bolt for clamping the arm and block together and to the base.

14. A key duplicating machine comprising a movable head having separated clamp-centering-and-holding seats, and similar interchangeable removable pattern and blank holding clamps fitted to said seats respectively and interlocking therewith against lateral displacement, and embodying clamping bolts entering said head and whereby the clamps are secured thereto, respectively, and whereby the clamps are opened and closed.

15. A key duplicating machine comprising a head having similar interchangeable pattern and blank holders, each holder embodying an upper and a lower jaw, a clamping bolt passing loosely therethrough and into the head, and a removable headed fulcrum pin, said jaws having grooves across their inner faces to removably receive said pin, one of said jaws being rockable on said pin, said jaws being independently reversible.

16. A key duplicating machine a head having a pattern holder, and a similar blank holder, each holder embodying a pair of reversible jaws and a device for actuating said jaws to grip the key or blank therebetween, each jaw provided with a rounded rib to enter the longitudinal side groove of a key or blank.

17. In a key duplicating machine and the like, a head provided with a holder consisting of a pair of co-operating jaws and a clamping screw passing loosely through said jaws for operating the holder, one of said jaws being rockable on a transverse axis and having a convexed outer surface, said screw having a shoulder to engage said surface in forcing said jaw against the work in clamping the same to the other jaw, said rockable jaw being reversible around said screw.

18. A key duplicating machine embodying a pattern holder, and a blank holder, each holder consisting of a clamping bolt and a pair of separate removable block-like jaws having aligned transverse bolt holes and formed with parallel corresponding grooves across their inner faces and at opposite ends, and a separate removable fulcrum pin resting in a pair of opposing grooves at corre-

sponding end portions of the jaws, one of the jaws being rockable on said pin.

19. A key duplicating machine embodying a head provided with a pattern holder and with a holder consisting of a pair of separate removable block-like jaws, and a headed clamping bolt passing loosely and approximately centrally therethrough and into said head to clamp the jaws together and thereto, each jaw at one end of its inner face having a straight rounded rib extending thereacross and at the opposite end of its inner face having a flat surface, said jaws being separately reversible end for end.

20. In a key duplicating machine and the like, a pattern holder and a corresponding blank holder, said holders being similar and interchangeable, and a head, said holders comprising means for removably and independently securing them to the head, each holder consisting of a pair of removable independently reversible clamping members.

21. In combination, in duplicating apparatus, a cutting tool, a head, said tool and head being relatively movable whereby the work is traversed by the tool, said head being provided with a pair of separated similar holder receiving-and-centering seats, a pair of similar interchangeable holders formed to removably interlock with said seats, respectively, one holder adapted to grip the work, and the other holder adapted to grip a pattern, and a gage to coöperate with said pattern.

22. A key duplicating machine and the like, provided with a holder comprising a jaw rockable on a transverse axis and having a longitudinally convexed outer surface, said jaw being reversible end for end, and holder operating means engaging said convexed surface of the jaw and forcing the jaw to clamp the work.

23. A key duplicating machine and the like, provided with a holder consisting of a pair of jaws separately and independently reversible end for end, and holder operating means for actuating the same to grip an article between said jaws, each jaw provided at its opposite ends with different gripping surfaces, substantially as described.

24. A key duplicating machine and the like, provided with a holder embodying a rockable jaw, and a holder operating device for actuating said jaw to grip the work, the gripping face of said jaw formed with a transversely rounded key or blank centering rib arranged to enter the longitudinal side groove of a key or blank, substantially as described.

25. A key duplicating machine and the like, provided with a holder comprising a rockable block-like jaw having a transverse bolt hole approximately midway between its ends, and a clamping bolt extending through said hole for actuating the jaw to clamp the

work, said jaw being reversible end for end on said bolt, said jaw having differently formed clamping faces at its opposite end portions.

26. A key duplicating machine and the like, embodying a head provided with a holder consisting of a pair of separate removable block-like jaws, and a clamping bolt passing loosely and approximately centrally therethrough and into said head to clamp the jaws together and to the head, said jaws being separately reversible around said bolt end for end, substantially as described.

27. In a key duplicating machine and the like, a head provided with a holder having a lower clamping member and a rounded fulcrum arranged transversely of one end portion thereof, an upper removable block-like clamping jaw reversible end for end and adapted to rock on said fulcrum, and operating means for said holder adapted to actuate said jaw to clamp the work against said member, said jaw having transverse grooves at the under sides of its end portions to receive said fulcrum.

28. In a key duplicating machine and the like, a head provided with a holder having upper and lower clamping jaws, a clamping screw passing transversely and removably through said jaws to operate the holder, said jaws having grooves across their inner faces, and a removable fulcrum pin in said grooves and on which the upper jaw is rockable, said pin having heads at the exteriors of said jaws to engage the edges thereof, and center the jaws.

29. In a duplicating apparatus, in combination, a cutting tool, a head movable freely toward and from said tool, means yieldingly holding said head toward said tool, feeding mechanism whereby the tool and head are relatively movable on the feed stroke transversely of said path of movement of the head toward and from the tool, a work holder mounted on the end of the head adjacent to said tool, a pattern holder mounted on the head in front of and spaced from said work holder and remote from the tool, and a gage fixed with respect to said head and its holders and extending over the head between said holders to coöperate with the pattern carried by said pattern holder in controlling the movement of the head toward and from the tool.

30. A key duplicating machine comprising a rotary cutting tool, a feed carriage movable on its feed stroke in a direction parallel with the axis of rotation of said tool, means for simultaneously rotating said cutting tool and actuating said carriage on its feed stroke whereby the speed of the carriage on its feed stroke bears a fixed relation to the speed of rotation of said tool, said carriage provided with means to hold a

blank to be cut in a position parallel with the direction of movement of said feed carriage and in position to be operated on by said tool, and also provided with means to hold a pattern in a position parallel with said blank, and a gage fixed with respect to said carriage and head and having a beveled tooth in engagement with the edge of said pattern to be duplicated.

10 31. A key duplicating machine, comprising a rotary cutting tool, a feed carriage movable on its feed stroke in a direction parallel with the axis of rotation of said tool, means for simultaneously rotating said cutting tool and actuating said carriage on its feed stroke whereby the speed of the carriage on its feed stroke bears a fixed relation to the speed of rotation of said tool, said means embodying manually controlled mech-

anism whereby said carriage can be operatively disconnected for return by hand, said carriage provided with means to hold a blank to be cut in a position parallel with the direction of movement of said feed carriage and in position to be operated on by said tool, and also provided with means to hold a pattern in a position parallel with said blank, and a gage fixed with respect to said carriage and head and having a beveled tooth in engagement with the edge of said pattern to be duplicated.

15 In testimony whereof I hereto affix my signature in presence of two witnesses.

EDWARD HOERNEL.
